UNITED STATES PATENT OFFICE.

JOHN LESTER MURRIE, OF NEW YORK, N. Y.

PROCESS AND APPARATUS FOR DECOMPOSING HYDROCARBON OILS AND WATER AND RECOMPOSING THE PRODUCTS THEREFROM.

Application filed March 27, 1922. Serial No. 547,316.

To all whom it may concern:

Be it known that I, JOHN LESTER MURRIE, a citizen of the United States, whose address is 74 Broadway, borough of Manhattan, county, city, and State of New York, have invented certain new and useful Processes and apparatus for decomposing hydrocarbon oils and water and recomposing the products therefrom into various other products, such as hydrocarbon oils of different characteristics from the untreated oil and also fuel and illuminating gases.

Broadly, my invention consists in causing, at a high velocity, an intermixture of oil and superheated water to impinge upon a similar opposing jet of oil and superheated water, whereby the oil and water are broken up into an extremely fine molecular condition and very completely vaporized, and thereafter subjecting the vapor so formed, under pressure, to a high degree of heat in a converting coil, whereby the molecules of oil and water are caused to combine in varying proportions, dependent on the pressure and heat, thereby forming new hydrocarbon products, which are rendered fixed and stable by the heat to which they are subjected in the generator coil.

The invention may be best explained by a description of the apparatus herein illustrated.

In the drawings, which are largely diagrammatic, Fig. 1 is a vertical partially sectional view of the apparatus; Figs. 2 and 3 are end elevations of the molecularizing jet head. Fig. 4 is a vertical and central sectional view of the molecularizing jet head; Fig. 5 is a horizontal and central section of the molecularizing jet head, showing the jets and Fig. 6 is a sectional view of one of the jets. In the drawings, similar figures and letters represent similar parts.

A. A represent the refractory walls of a furnace of any suitable construction, through wall A of which passes a pipe 1 connecting water tank D with the superheating coil 2. The superheating coil 2 connects by pipe 3 with the atomizer B. Pipe 4 connects oil tank C with the atomizer B. 5 is a converting coil connecting at its upper end 6 with atomizer B and at its lower end with outlet head 7. 8 is a burner arranged for burning gas or oil, and shown for burn-

ing gas, and is connected by pipe 8' to a 55 source of gas and by pipe 9 to the outlet pipe 10 from the generating coil 5. The burner 8 is also connected by pipe 11 to a source of compressed air. Water tank D is connected by pipe 12 and oil tank C is 60 connected by pipe 13 to pipe 14, which in turn is connected to a source of compressed air. 15 is a drain pipe for the converting coil 5 and 16 is a plug by means of which access may be had to the interior of converting coil 5. 17 and 18 are drain pipes for tanks C and D. 19 and 20 are plugs by means of which tanks C and D can be respectively filled with oil and water. E is a condenser consisting of a closed case 19 70 and coil 20, coil 20 being connected at its inlet end to pipe 10 and at its outlet end to pipe 21. Condenser E is also connected by pipe 22 to a source of water supply and by pipe 23 to a water overflow. Pipe 21 75 connects to a condensate tank F, which in turn is connected by pipe 24 with a gas tank G. 25 and 26 are drain pipes for tanks F and G respectively. 27 is a spring pressure relief valve for controlling the pressure in condenser coil 20 and 28 is a pressure gauge indicating the pressure in condenser coil 20. S is a stack for carrying away the products of combustion from furnace A. A' is a stack damper. a. b. c. 80 d. e. f. g. h. i. j. k. l. m. n. o. p. q. are valves controlling the various pipes in which they are inserted. r and s are check valves in oil pipe 4 and water pipe 1 respectively, to prevent any back action from the liquids 85 passing therein.

B is an atomizer, consisting preferably of a cross shaped chamber 30. 30. with four openings, each respectively closed by a removable head 31, 32, 33, 34. The upper 95 end 6 of converter coil 5 is inserted in head 33 and head 34 is provided with a pressure gauge 35. The outlet pipe 3 of superheated water coil 2 is branched at 40 into pipes 36 and 37 and the oil supply pipe 4 is branched at 41 into pipes 38 and 39. 42 and 43, 42' and 43' are manifolds, manifold 42 being connected to the superheated water pipe 36 through needle valve v and pipe 44, manifold 43 being connected to the oil pipe 39 100 through needle valve w and pipe 45, manifold 42' being connected to the superheated water pipe 37 through needle valve v' and

pipe 44' and manifold 43' being connected to the oil pipe 38 through needle valve w' and pipe 45'.

Inserted through heads 31 and 32 and connected to and controlled by needle valves s, t, u and s', t', u' , are injector type jets J and J' shown in detail in Fig. 6, arranged diametrically opposite in pairs as shown. Any number of pairs of jets may be used, 10 three pairs being shown in the drawings. Each of these jets, see Fig. 6, consist of an inner tube X and an outer encircling tube Z, the inner tube being connected to the oil source and the outer tube being connected 15 to the superheated water source through needle valves s, t, u and s', t', u' . s, t, u and s', t', u' are needle valves so arranged and connected to the manifolds 42, 43 and 42', 43' and the jets J, J, J and J' J' J' as to 20 control the flow of oil to the jets J and J'.

The preferred construction of these jets is shown in Fig. 6 in which X is the inner tube and Z the outer encircling tube. The inner tube X is connected through the orifice 55 with the oil inlet 53 and the outer tube Z is connected through opening 46, 46, between it and inner tube X with the superheated water inlet 52. 54, 56 is a screw-threaded needle valve stem which by means 30 of handle H controls the size of the opening 55 and so the amount of oil permitted to flow therethrough. 28, 35 and 35' are pressure gauges and 57 and 58 are pyrometers for determining the pressures and temperatures 35 in the various parts of the apparatus. 59 is a spring safety valve to control the pressure in the system. The whole system operates automatically, continuously, and under pressure at all times.

40 The needle valves permit the supply of oil to each jet to be controlled separately, which is of importance in the practical operation of the invention.

The operation of the system is as follows:

45 The oil and water tanks C and D being filled with oil and water, the burner 8 being put in operation and the furnace A. A' heated up to the desired temperature, about 1200° F. to 1400° F., controlled air pressure 50 is applied, by means of valves a and c , to the oil and water tanks C and D, thereby causing the oil and water to flow through pipes 4 and 1, such flow being controlled by valves b and d . The water passes into the 55 superheating coil 2 where it is raised to a high temperature, but being confined, cannot change into steam until released. The pressure employed will depend upon the temperatures used, since it must be sufficient 60 to prevent the vaporization of the water. The temperature employed will depend upon the character of the oil being treated, and the particular result which it is desired to attain. The superheated water 65 passes from coil 2 through pipe 3 to con-

nnection 40, where it divides and passes through pipes 36 and 37, needle valves v and v' and pipes 44 and 44' to manifolds 42 and 42'. At the same time the oil flows 70 through pipe 4 to connection 41, where it divides and passes through pipes 38 and 39, needle valves w and w' and pipes 45 and 45' to manifolds 43 and 43'. Its further progress is controlled by the needle valves s, t, u , and s', t', u' , which, when opened, permit the oil to pass through the central tube 48 (Fig. 6) in jets J and J' issuing at the opening 51, where it is caught up by the steam issuing at 50, where the steam vaporizes the oil and intermingles with it and imparts its force and velocity to it. This action takes place at the orifices of all six jets, and as these jets are arranged in pairs, axially opposite each other, the opposed streams of intermingled steam and oil strike each 80 other at high velocity and with great force. The effect of such impact is to produce an extremely fine atomized condition of the meeting fluids, which thoroughly breaks down the chemical combinations of hydrogen and oxygen, forming the steam, and the chemical combinations of carbon and hydrogen forming the oil, and to release the molecules of hydrogen, oxygen and carbon 90 into a free state, entirely disassociated from each other and at the same time to form a very intimate mixture of these molecules. The vapor thus formed is under pressure, which is controlled by the amount of superheated water and oil permitted to pass to 100 the jets. The molecular vapor then passes through pipe 6 into the converting coil 5, where under the influence of combined heat and pressure, the molecules of hydrogen, oxygen and carbon reunite to form new 105 hydro-carbon compounds entirely different from the original hydrocarbon or oil supplied to the apparatus, such compounds being dependent in character on the temperatures and pressures under which they are 110 formed, different combinations of heat and pressure forming different hydrocarbon compounds.

These compounds are stabilized and fixed 115 in the converting coil, whence in vapor or gaseous form they pass through union 7, pipe 10 and valve k to a condenser E, which may be of any desired form, the one shown 120 consisting of a coil 20 enclosed in a casing 19 through which water is allowed to flow through pipe 22, valve m , condenser casing 19, valve l and pipe 23. As all of the condensing is performed under pressure in the condensing coil 20, a gauge 28 is provided 125 for showing the pressure in the condensing coil and a spring release valve 27, which may be set to any desired pressure is placed in the outlet pipe 21. The condensate passes through pipe 21 and valve o into a storage tank F, from which it may be 130

drawn, as desired, through a valve *p* and outlet pipe 25. If it is desired to retain the gas in an uncondensed state, it may pass through condenser coil 20, without any cooling liquid flowing through the condenser tank 19, through pipe 21, condensate tank F, valve *n* and pipe 24 into a gas tank G, where it may be stored for further use and from which it may be drawn through valve 10 *g* and pipe 26.

I call particular attention to the fact that I employ superheated water not steam, whereby I secure the utmost speed at the nozzles and the instantaneous flashing into vapor immediately upon release from the nozzles, which materially contributes to the disrupting or atomizing action.

It will be obvious to those who are familiar with such matters that any preferred number of jets may be employed and also that other departures may be made from the details of construction of the apparatus described and illustrated by me and yet the essentials of my invention be utilized, for example, although it is preferable to utilize a mixture of oil and superheated water in each jet, yet it is possible to employ jets so arranged that oil may be projected from one set of jets and superheated water from the opposite jets; also although I much prefer that the jets should be opposed to each other as described, because then the impact of the rapidly moving opposed fluids upon each other is accentuated and the disrupting effect increased because they meet while both are moving at high velocity in opposite directions, still satisfactory results may be secured, especially in the treatment of oils of certain quality or in special conditions, if the combined superheated water and oil be projected against any suitable obstruction, in such case, however, the pressure and consequently the velocity should usually be increased. I therefore do not limit myself in any respect thereto, on the contrary, desire protection for my invention as broadly as the claims below imply:

I claim:

1. The described process consisting in superheating water under pressure, then combining the superheated water with oil, forthwith conveying the mixture thence to a vaporizing chamber and projecting the mixture under pressure against an obstructing substance within said vaporizing chamber, conducting the resulting vapors under pressure through a specially heated converting coil and condensing and removing the product.

60 2. The described process consisting in superheating water under pressure then combining the superheated water with oil, forthwith conveying the mixture thence to a vaporizing chamber and projecting the 65 fluid mixture in opposed streams through axially opposed nozzles within said vaporizing chamber, conducting the resulting vapors under pressure through a specially heated converting coil and condensing and 70 removing the product.

3. The described process consisting in conveying water under pressure through a heating coil within a furnace where it is superheated under pressure, then mixing oil 75 under pressure with the superheated water, immediately after such admixture conveying the same to a series of opposed nozzles located within an enclosed vaporizing chamber, regulating the passage of the mixture 80 through the opposed nozzles to produce the desired velocity and atomizing result, conducting the resulting vapors through a specially heated converting coil and condensing and removing the product.

85 4. As steps in an oil converting process continuously superheating water under pressure, then continuously mixing the same with oil under pressure, and immediately and continuously releasing the mixture 90 under pressure against an obstruction which causes impact within an enclosed atomizing chamber and continuously conducting the resulting vapors through a specially heated converting coil and continuously removing the product.

5. In apparatus of the class stated, a water tank, an oil tank, means to generate pressure in each tank, a furnace, a water superheating coil within the furnace, a pipe connection between said water tank and said water superheating coil, an enclosed atomizing chamber, pipes connecting the water coil and the oil tank with a nozzle which discharges into the atomizing chamber, a converting coil within the furnace, a pipe connection between said atomizing chamber and said converting coil, a condenser connecting with the converting coil, and means to convey away and store the product.

105 JOHN LESTER MURRIE.
